UNITED STATES PATENT OFFICE

135,672

DESIGN FOR A COIN BANK

Ralph Victor Moran, Bradford, Pa.

Application March 3, 1943, Serial No. 109,649

Term of patent 14 years

To all whom it may concern:

Be it known that I, Ralph Victor Moran, a citizen of the United States, residing at Bradford, in the county of McKean and State of Pennsylvania, have invented a new, original, and ornamental Design for Coin Banks, of which the following is a specification, reference being had to the accompanying drawing, forming part thereof.

In the drawing:

Fig. 1 is a front elevational view of a coin bank, showing my new design;

Fig. 2 is a vertical sectional view taken on the line 2—2 in Fig. 1, looking in the direction of the arrows; and

Fig. 3 is a horizontal sectional view taken on the line 3—3 of Fig. 1, looking in the direction of the arrows.

I claim:

The ornamental design for a coin bank, as shown.

RALPH VICTOR MORAN.
